UNITED STATES PATENT OFFICE.

XAVIER JUNGE, OF VENTURIA, NORTH DAKOTA.

STOVEPIPE COUPLING.

Application filed November 1, 1921. Serial No. 512,038.

To all whom it may concern:

Be it known that XAVIER JUNGE, a citizen of the United States of America, residing at Venturia, in the county of McIntosh and 5 State of North Dakota, has invented new and useful Improvements in Stovepipe Couplings, of which the following is a specification.

The object of the invention is to provide 10 a simple and efficient means whereby the adjoining telescoped extremities of stove pipe and similar sections may be secured against disengagement by relative longitudinal movement; and with this object in view the invention 15 consists in a construction and combination of parts of which a preferred embodiment is shown in the accompanying drawings, wherein:—

Figure 1 is a view of a stove pipe coupling or holding device embodying the invention applied in the operative position to a 20 stove pipe joint, a portion of the stove pipe being broken away.

Figure 2 is a detail view of the coupling 25 or holder detached but shown in the position which it occupies when applied to the pipe.

Figure 3 is a view of the coupling or 30 holder as it is constructed and appears as an article of manufacture prior to application to the stove pipe.

The stove pipe coupling or holder embodying the invention consists essentially of a blank or length of rod or heavy wire 10 preferably of spring or tempered material 35 and provided with terminal spurs 11 sharpened and adapted to be driven into or engaged with punctures 12 in the walls of the stove pipe sections 13 which are connected by an overlapped or telescoping joint indicated in Figure 1, the spurs at opposite ends 40 of the holder or coupling respectively engaging the different jointed lengths of the stove pipe joint as to resist any tendency of the pipe sections or lengths to move away 45 from each other and thus open the joint between the same. Obviously any desired number of these holders or coupling elements may be used at a joint of pipe, two being indicated in Figure 1.

As originally constructed the holder or

coupling is preferably given an arcuate or coiled form as shown in Figure 3, as when applied to the joint between pipe sections it is straightened as shown in Figure 1 so as to lie substantially parallel with the pipe 55 walls under tension so that the tendency of the holder to resume the original or normal position indicated in Figure 3 serves to firmly hold the spurs in engagement with the punctures in the pipe sections. The 60 spurs are preferably inturned or deflected inwardly toward their extremities as clearly indicated in Figure 2 so that the tendency of the body portion of the device to assume a curved form tends not only to firmly hold the spurs in their engaged position but to draw the pipe sections toward each other and effectively resist any tendency of the 65 same to move in the opposite direction and thus become disengaged. 70

Having described the invention, what is claimed as new and useful is:—

1. A stove pipe holder or coupling consisting of a terminally spurred blank of wire or rod adapted for arrangement longitudinally of a length of pipe in spanning relation with the joint between sections thereof and having its spurs engaged with punctures in said pipe sections. 75

2. A stove pipe holder or coupling consisting of a terminally spurred blank of wire or rod adapted for arrangement longitudinally of a length of pipe in spanning relation with the joint between sections thereof and having its spurs engaged with punctures in said pipe sections, said blank being of spring or resilient material and normally having an arcuate form. 80

3. A stove pipe holder or coupling consisting of a terminally spurred blank of wire or rod adapted for arrangement longitudinally of a length of pipe in spanning relation with the joint between sections thereof and having its spurs engaged with punctures in said pipe sections, the terminal 85 spurs being inwardly directed toward their extremities. 90

In testimony whereof he affixes his signature,

XAVIER JUNGE,
